UNITED STATES PATENT OFFICE.

AXEL E. JACOBSON, OF MINNEAPOLIS, MINNESOTA.

GRINDING-MILL.

1,374,207.

Specification of Letters Patent. Patented Apr. 12, 1921.

Application filed April 7, 1919. Serial No. 288,106.

To all whom it may concern:

Be it known that I, AXEL E. JACOBSON, a citizen of the United States, residing at Minneapolis, in the county of Hennepin and State of Minnesota, have invented certain new and useful Improvements in Grinding-Mills; and I do hereby declare the following to be a full, clear, and exact description of the invention, such as will enable others skilled in the art to which it appertains to make and use the same.

My invention relates to improvements in mills for grinding grain, feed and the like, and has for its object to provide therefor a highly efficient grinding surface.

To the above end, the invention consists of the novel devices and combination of devices hereinafter described and defined in the claims.

In the accompanying drawings, which illustrate the invention, like characters indicate like parts throughout the several views.

Referring to the drawings:

Figure 1 is a view principally in vertical section taken on the line 1—1 of Fig. 2, and illustrating a grinding mill having the invention incorporated therein;

Fig. 2 is a transverse section taken on the line 2—2 of Fig. 1;

Fig. 3 is a transverse section taken on the line 3—3 of Fig. 1;

Fig. 4 is a perspective view of the grinding and screening cylinder, removed from the mill;

Fig. 5 is a fragmentary detail view, on an enlarged scale, showing the inner face of the grinding and screening cylinder;

Fig. 6 is a detail view in section taken on the line 6—6 of Fig. 5; and

Fig. 7 is a detail view in section taken on the irregular line 7—7 of Fig. 5.

The numeral 8 indicates a base having converging sides and its top is provided with a segmental depression 9 which extends transversely and centrally between the ends of said base. This depression 9 is also further centrally depressed to afford a concentric segmental seat 10 which extends to the converging sides of the base 8. A cylindrical housing 11, having an open bottom, is supported in the depression 9 by forming therewith outturned segmental flanges 12 which rest on said depression. The housing 11 is further supported from the base 8 by integrally forming with the ends of said housing, horizontally outturned flanges 13, lo-

cated above the flanges 11, supported on the top of the base 8, outward of the depression 9, and rigidly bolted thereto.

Cast pockets 14 having open tops and converging side walls are rigidly secured by bolting the same to the oblique walls of the base 8. The open tops of the pockets 14 extend into the open bottom of the housing 11 with their upper edges located the same distance from the axis of the housing as the inner face of said housing. Said pockets 14 are further secured to the housing 11 by providing said housing with outturned radial flanges 15, which overlap said pockets 14 and are bolted thereto. In the bottoms of the pockets 14 are cover equipped hand holes 16.

Formed in the housing 11, at the right side thereof, is an eccentrically located segmental air chamber 17 which is open throughout its entire length, to the interior of the housing 11 and extends from the pockets 14 over and above said housing. In the top of the housing 11 is a displaceable section or cover 18, which extends the full length thereof and is detachably secured in position by nut-equipped bolts 19, passed through aligned bores formed in outturned radial flanges 20 integrally formed with said housing 11 and its top section 18. Formed in the housing section 18, at the top of the air chamber 17, is a flanged discharge opening 21 to which is bolted, a discharge pipe 22, leading to a storage bin or the like, not shown.

A power shaft 23 is loosely extended axially through openings in the heads of the housing 11 and journaled in ball bearings 24, at the ends of the base 8, and has secured to its right hand end, as shown in Fig. 1, a pulley 25. The opening in the left hand end of the housing 11 is considerably larger than the shaft 23 to afford a grain intake eye 26. A relatively large outwardly projecting U-shaped guard 27 is secured to the left hand head of the housing 11, and surrounds the lower one-half of the eye 26 and its upper end portions extending to the top of said housing.

To the upright members of the guard 27 is secured a horizontally disposed oblique deflecting board 28 which overlies the eye 26. A bracket 29 is bolted to the displaceable section 18 of the housing 11 and is provided with a vertical discharge opening 30, located partly over and partly outward of the deflecting board 28. The flanged lower

end of the grain supply pipe 31 rests upon the bracket 29 and is bolted thereto, and leads from a hopper or other suitable source of supply, not shown.

- 5 Keyed to the shaft 23, for rotation therewith, in the housing 11, are two axially spaced spiders 32 in the form of annular rims connected by radial arms to the hub in said shaft. The hubs of the spiders 32 are
 10 arranged to engage the ends of the housing 11 and thereby hold said spiders against axial movement in said housing. The rims of the two spiders 32 are connected by a plurality of circumferentially spaced horizontal
 15 rods or shafts 33, loosely inserted through alined holes in the rims of said spiders and project outward thereof.

Carried by each rod 33 are several sets of beaters, each of which comprises a multiplicity of rectangular sheet metal plates 34, held between and laterally spaced by sheet metal plates 35. These beater and spacing plates of each set are rigidly connected by bolts or rivets 36 and, it will be noted, that
 25 the two outer plates 35 are somewhat thicker than the inner of said plates to give the required rigidity to the beaters. It will also be noted that the outer ends of the beater plates 34 extend outward of the spacing plates 35 to afford a plurality of fingers having sharp cutting corners for coöperation with the improved grinding surface, as will presently appear. The several sets of beaters are pivotally secured to the respective rods
 30 35 by forming therein, near their inner ends, bores through which said rods project. Each beater is held against axial movement on the respective rod 33 by the adjacent spider 32 and a cotter pin 33'.

- 40 The improved grinding surface, heretofore referred to and with which the beaters coöperate, to produce the grinding action of the mill, is formed with a cylinder 37 mounted in the housing 11 and provided with a screening surface, as will hereinafter appear. This cylinder 37 extends the full width of the housing 11 and comprises a top section 38, a bottom section 39 and two side sections 40. The top cylinder section
 45 50 38 bears against the inner face of the top section 18 of the housing 11 and the bottom section 39 rests upon a segmental plate 41 supported in the seat 10.

To hold the several sections of the cylinder 37 in the proper positions in the housing 11 and against circumferential movement therein, the ends thereof are bent radially outward to afford anchoring flanges 42 which extend in seats 43. The seats 43 for the flanges 42 on the top section 38 and the upper flanges 42 on the side sections 40 are formed between the housing flanges 20. The seats 43 for the lower flanges 42 on the side sections 40 are formed between the
 60 65 pockets 14 and housing flanges 15, while

the seats 43 for the bottom section 39 are formed between the pockets 14 and ends of the plate 41.

The grinding surface of the several sections of the cylinder 37 is produced by transversely cutting and pressing inward therefrom, loops 46 in staggered arrangement. These loops 46 have a concavo-convex formation, in respect to the direction of rotation of the beaters, to afford, on their inner or concave faces, two sharp cutting edges 47. Either of these cutting edges 47 may be used by changing the direction of rotation of the shaft 23. This grinding surface covers the entire surface of the lower cylinder section 39 and only about one half of the width of the cylinder sections 38 and 40.

The other one half of the width of the cylinder sections 38 and 40 are perforated to afford a screen 48 which separates the main housing 11 from the air chamber 17. The openings in the cylinder 37 produced by the formation of the loops 46 and which afford the grinding surface of the mill are closed in the sections 38 and 40 by the shell of the housing 11 and in the section 39, by the plate 41.

Operation.

The operation of the grinding mill may be briefly described as follows, to wit:—

The shaft 23 is driven at a very high number of revolutions per minute and the suction produced by the spiders 32 and beaters, draws grain, precipitated from the spout 31, through the eye 26 and into the housing 11, as indicated by arrows marked on Fig. 1.

The grain, as the same is held against the cutting edges 47, nearest the approach of the beaters, which are held outward under centrifugal force, is caught by said beaters, crushed or cut and driven through the loops 46. From the housing 11 the ground feed is forced through the screen 48 into chamber 17 by the blast produced by the spiders 32 and beaters. This same blast also forces the ground feed from the chamber 17 and through the pipe 22, as indicated by arrows marked on Fig. 2.

Any hard foreign matter, drawn into the housing 11, such as nuts, will be caught in the pockets 14 and held out of the path of movement of the beaters. While the pockets 14 are usually filled with grain and feed, a relatively heavy object caught in either of said pockets will settle therein. The contents of these pockets 14 may be emptied from time to time by opening the hand holes 16.

The improved grinding surface of the mill will keep sharp throughout the life thereof and is operative in either direction of rotation of the shaft 23. Owing to the

width of the loops 46, the improved grinding surface will last a long time.

It is, of course, understood that the sections of the cylinder 37 may be independently replaced when worn out. In place of forming the grinding and screening surfaces of each section with an integral plate, said plate may consist of two members, the one containing the grinding surface and the other, the screening surface, so that said members may be independently replaced when worn out or for other purposes.

What I claim is:

1. The combination with a housing, of a segmental plate in the housing having cut and pressed therefrom loops which constitute a grinding surface thereon, both ends of the loops being integral with the plate, the under faces of said loops being spaced above the upper face of the plate, and revoluble beaters mounted in the housing for coöperation with said grinding surface and arranged to move transversely over said loops.
2. The combination with a housing having a closed segmental surface, of a segmental plate directly and removably supported

on said surface and having cut and pressed therefrom loops which constitute a grinding surface thereon, both ends of the loops being integral with the plate, the under faces of said loops being spaced above the upper face of the plate, and revoluble beaters mounted in the housing for coöperation with said grinding surface and arranged to move transversely over said loops.

3. The combination with a housing, of a segmental plate in the housing having cut and pressed therefrom loops which constitute a grinding surface thereon, both ends of the loops being integral with the plate, the under faces of said loops being spaced above the upper face of the plate, said loops being concavo-convex in cross section, and revoluble beaters mounted in the housing for coöperation with said grinding surface and arranged to move transversely over said loops.

In testimony whereof I affix my signature in presence of two witnesses.

AXEL E. JACOBSON.
